PAGE 2

FIG. 2

FIG. 3

FIG. 1 is a front elevational view of a sink trap embodying my new design;

FIG. 2 is a perspective view taken from the front and bottom thereof; and

FIG. 3 is a perspective view taken from the rear and bottom thereof.

The broken line representation of a sink and drain pipe in FIG. 1 and drain pipes in FIGS. 2 and 3 are for purposes of illustration only.

I claim:

The ornamental design for a sink trap, substantially as shown and described.
